UNITED STATES PATENT OFFICE.

WILLIAM N. WEINMAN, OF COLUMBUS, OHIO.

PUMP.

Application filed April 19, 1923. Serial No. 633,307.

To all whom it may concern:

Be it known that I, WILLIAM N. WEINMAN, a citizen of the United States, residing at Columbus, in the county of Franklin and 5 State of Ohio, have invented certain new and useful Improvements in Pumps, of which the following is a specification.

The present invention is directed to improvements in pumps, and more particularly 10 to that type used in mines.

The primary object of the invention is to provide a gear operated pump so constructed that the operating gears and the associated driving connections will be constantly oiled.

15 A further object of the invention is to provide a pump so constructed that the pump piston can be easily and quickly removed from its cylinder without the necessity of disassembling the piston driving mechanism.

20 With these and other objects in view, as will appear as the description proceeds, the invention consists in the novel features of construction, combinations of elements and arrangements of parts, as hereinafter to be 25 fully described and pointed out in the appended claim.

In the accompanying drawing:

Figure 1 is a side elevation of a pump, partly in section, and with the gear casing 30 cover removed, and

Figure 2 is a sectional view on the line 2-2 of Figure 1.

Referring to the drawing 1 designates a base, and carried thereby is a gear casing 2, 35 the rear wall 3 of which has supported thereon a stub shaft 4 and to which is fixed the gear 5.

The gear 5 carries an eccentrically mounted pin 6 upon which is loosely mounted a 40 block 7, the purpose of which will appear later. Associated with the gear 5 is a yoke 8 which consists of complementary spaced sections 9 and 10 which are provided with horizontal guide rods 11 and 12, respectively, 45 the latter being slidably engaged in the tubular head 13 carried by the rear end of the gear casing 2. The block 7 is slidable in the space 14 provided between the sections 9 and 12, and has its sides in intimate contact with the confronting faces of the 50 respective sections.

The rod 11 is slidable in the inner side of the casing 2, and threaded in the outer end thereof, as at 15, is the inner end of the 55 piston rod 16 of the pump piston head 17, said piston being reciprocable in the pump

cylinder 18. The rod 16 is slidable in the stuffing box 19 which is carried by the plate 20, said plate constituting a head for the rear end of said cylinder. This plate is 60 clamped between the cylinder end and the forward circular end 21 of the frame 22, said frame being an integral part of the gear casing 2, and has an open side 23 so that the threaded connection between the rods 11 and 16 is readily accessible, and owing to this, the piston rod 16 can be readily disengaged from the rod 11 without disturbing the yoke and its driving mechanism, and when it is 65 desired to remove the piston head 17 from 70 its cylinder. The outer end of the cylinder is closed by the head 24, which when removed permits the piston head and its rod 16 to be readily removed.

A cover plate 25 is removably connected 75 to the gear casing 2, and is provided with a filling plug 26 through which oil is poured into the casing 2 to a predetermined level, or to a level to assure proper lubrication to the yoke and its associated parts. Thus it 80 will be seen that lubrication of the yoke and its associated parts is assured.

A shaft 27 is carried by the casing 2 and has fixed to its inner end a pinion 28 which meshes with the gear 5, said shaft having 85 fixed to its outer end a gear 29, and meshing with this gear is a pinion 30 which is driven in any suitable manner, as for instance by an electric motor.

The gear 29 and associated pinion 30 are 90 enclosed by a casing 31 to protect the same from moisture and grit.

It will be apparent that when the gear 5 is rotated that the blocks 7 will be driven in a circular direction, and will consequently 95 cause the yoke 8 to reciprocate together with the rod 11 and rod 16, thus imparting to the piston head 17 the necessary pumping action.

Pumps of this character are used for pumping water from mines and this water oftentimes contains alkali which is injurious to the metallic parts. It will be observed that the piston rod 16 which travels in the stuffing box 19 has engaged thereon the hub 32 of the disk 33, said disk having a marginal skirt formed therewith. It sometimes occurs that water will leak through the stuffing box 19 and splashes upon the horizontal guide rod 11 and would tend to seep into the casing 2, but owing to presence of the disk 33 any possibility of water seeping into this casing is positively eliminated. Fur- 100 105 110

ther it will be observed that the hub 32 serves as a jamb nut for the connection between the piston rod 16 and the rod 11.

What is claimed is:

- 5 In a self contained, self oiling pump, a unit comprising a circular, vertically disposed, oil tight chamber in which oil is maintained at a predetermined level having a removable front plate, a base, an open side
- 10 tubular extension projecting horizontally from said chamber upon one side thereof and terminating at its outer end in a flanged portion and a bearing extension upon said chamber and lying outwardly thereof, all
- 15 of the foregoing except said front plate being formed as an integral piece, a large gear mounted for rotation in the circular chamber, a crank pin carried by said gear wheel, a block with which the crank pin is en-

gaged, a Scotch yoke with which the block 20 is slidably engaged, oppositely projecting guide rods carried by the yoke and sliding in diametrically opposed bearings located at the opposite sides of the circular oil chamber, a pinion meshing with the large gear 25 wheel, a shaft upon which said pinion is mounted, said shaft being journaled in the said bearing extension of the chamber with the teeth of the pinion projecting into said casing, the block dipping into the oil in the 30 casing to lubricate the block and yoke and the rotation of the gear elevating the oil and causing some of it to fall upon the guide rods, and carrying some of the oil into contact with the pinion whence it finds its way 35 to and lubricates the pinion shaft.

In testimony whereof I affix my signature.

WILLIAM N. WEINMAN.
